(57) CLAIM

I claim the ornamental design for a jewelry pendant, as shown and described.

DESCRIPTION

FIG. 1 is a perspective view of a jewelry pendant showing my new design;

FIG. 2 is a front elevational view of FIG. 1;

FIG. 3 is a rear elevational view of FIG. 1;

FIG. 4 is a left-side elevational view of FIG. 1, the right-side elevational view being a mirror image thereof;

FIG. 5 is a top plan view of FIG. 1; and,

FIG. 6 is a bottom plan view of FIG. 1.

The broken lines showing artwork and text in FIGS. 1 and 2 depict environmental matter and form no part of the claimed design.
